UNITED STATES PATENT OFFICE.

CASPER W. MILES, OF ANDERSON TOWNSHIP, HAMILTON COUNTY, OHIO.

METHOD AND APPARATUS FOR VENTILATING AND REFRIGERATING.

1,252,472.

Specification of Letters Patent.

Patented Jan. 8, 1918.

Application filed June 14, 1915. Serial No. 34,108.

To all whom it may concern:

Be it known that I, CASPER W. MILES, a citizen of the United States, residing at Anderson township, in the county of Hamilton and State of Ohio, have invented certain new and useful Improvements in Methods and Apparatus for Ventilating and Refrigerating, of which the following is a specification.

10 My invention relates to improvements in method and apparatus to ventilate and cool or refrigerate public or other buildings. One of its objects is to provide an ample supply of cool air in the portion of the room or 15 rooms where the occupants are located and to provide for its replacement with fresh air without excessive waste of refrigerating energy. Another object is to provide for the economical separation and removal of heat 20 developed or introduced into the room. Another object is to provide a purified dry and cooled air. Another object is to provide for storing up refrigerating energy for considerable periods of time and rendering the 25 same available during short periods when the room is occupied by large numbers of people. Another object is to provide improved apparatus for continuously carrying out my improved method of ventilating and 30 cooling. My invention also comprises certain details of form, combination and arrangement and order of procedure, all of which will be fully set forth in the description of the accompanying drawings in 35 which:

Figure 1 is a vertical section through a building containing a public hall, theater, or the like room, and illustrating my improved apparatus employed in ventilating 40 and cooling the same.

Fig. 2 is a vertical sectional detail of the air inlet and exit temperature or heat exchanger.

Fig. 3 is a top plan, partly in section of a 45 portion of the air cooling apparatus.

The accompanying drawings illustrate the preferred embodiment of my invention in which A represents a public hall such as a church, theater or the like in which a large 50 number of people are to be assembled and in warm weather require the air to be cooled as well as to be frequently replaced to render the occupants cool and comfortable. A' represents seats for the occupants. In order to 55 economically cool or refrigerate the air of the room as well as ventilate it, I provide

for keeping the air of the room separated by gravity into a warm stratum in the upper portion which is unoccupied and a cool stratum in the lower portion which is occupied by the people. Thus the cool lower stratum causes any heated air which is admitted to the room or exhaled by the people, or heated by contact with the people or illuminating apparatus to quickly rise to the upper part of the room, and separate itself from the cool lower stratum. This heated air is discharged direct to the atmosphere through a vent or draft tube B at the top of the room, and the rapidity of the discharge 70 is controlled according to the external temperature, the number of people, etc., first by means of a series of valves 2 which are opened or closed preferably by means of rack bars 3 actuated by a solenoid or other electrically actuated mechanism in a housing 3' controlled between definite limits by an electrical thermostat 4, and further controlled if necessary by means of an electrically driven fan 5 to cause an increased volume of air to 80 escape through the vent B over what would escape by natural draft. By thus regulating the escape of heated air through the vent B to meet varying conditions practically all of the heated air separates from the cool air 85 and is eliminated from the room and at the same time the relative depth of the cool stratum is uniformly maintained so that the people are submerged in air of the cool stratum. 90

The air of the cool stratum is to be circulated to and from the room, but in relatively less volume than would otherwise be required and being materially cooler than the external air it can not be economically 95 wasted or vented direct to the open air until after its negative heat value has been recovered to be further utilized. This is attained by withdrawing a regulated volume of cool air from the lower portion of the 100 side walls of room A, or if desired from openings at or near the floor. As illustrated 6 represent exit conduits for withdrawing cool air from room A. From the conduit 6 the cool air is conducted through a conduit 105 7 to a circulating fan 8 which forces it through a series of tubes 9 and thence through a conduit 9' to the open air. The fresh air to be taken into the room A is received preferably from an elevated location where as pure and cool an air supply as possible is available into the upper end of a 110

stack or conduit D down which it may be drawn in regulated quantity by a circulating fan or blower 10. At the lower end of the stack D is a chamber 11 inclosing the 5 tubes 9, where the fresh air from stack D comes into contact with the exterior of tubes 9 and is cooled by or exchanges temperature with the cool air passing out of room A through the tubes 9. From the chamber 11 10 the fresh air passes by conduit 12 to a chamber 14 where preferably all of it passes through a fine spray of cold water issuing from perforations in the under side of the horizontal tubes 15. The contact of the air 15 and cold spray serves to further and materially cool or refrigerate the air at the same time extracting therefrom its surplus moisture and practically all dust and germs of impurities.

20 In order to separate the air from any mist or fine particles of moisture due to cooling it with the spray, it is passed through a screen 16 preferably of thin cotton cloth supported upon and able to travel over a 25 series of rollers 17, thereby providing a screen capable of being removed and cleaned and replaced with another when desired. From the chamber 14 the air passes through a conduit 18 to a distributing conduit 19 30 from which it is discharged into the room A, preferably upon the opposite side from which cool air is withdrawn from room A. The cool air upon entering room A distributes itself in a substantially uniform stratum 35 occupying all of the lower portion of room A where it remains until either heated so as to rise and escape by exit B or until it is withdrawn through the exit 6. Any air which has been heated by respiration or direct contact with the occupants of the room 40 will immediately rise and escape by the exit B.

E represents a water storage tank in which are immersed a series of refrigerating coils 45 20 and 20' either or both of which are kept cool by means of an ice machine compressor 21 and condenser 22. The water in the tank E is preferably fresh water and may be reduced to any desired temperature not below 50 its freezing point, although a considerable body of ice may if desired be frozen upon the exterior of the coils 20 or 20' to serve as a reserve or accumulated body of refrigerant to be drawn upon when required. The 55 tank E is also of a size to hold a reserve supply of water to be cooled. This enables the refrigerating machine to be of relatively smaller capacity than otherwise necessary, and allows the refrigerating machinery to 60 be operated continuously storing up refrigerating energy in the water of tank E so that it may all become available during the few hours per day or per week, that refrigeration of the air supply of room A is required. The fresh water from tank E is

forced by pump 24 through the conduit 25 to the perforated tubes 15, and is returned from the bottom of chamber 14 to the tank E by a pipe 26 and pump 27.

The several doors 28 are practically the 70 only openings leading to the lower or cool portion of room A, and these doors preferably open outwardly and have close fitting joints protected by cushions or weather strip material to prevent any considerable escape 75 or loss of cool air from the lower portion of room A. The cooling system is also applicable to the separate rooms of a hotel or office building if desired.

My invention as herein disclosed is capable of considerable modification without departing from the principle thereof.

Having described my invention, what I claim is:—

1. The method of ventilating and refrigerating which comprises maintaining in a room an upper stratum of relatively warm air and a lower stratum of air of temperature lower than that of the external atmosphere, removing warm air from said upper stratum, and supplying air of lower temperature than that of the external atmosphere to maintain said lower stratum of air of substantially uniform volume.

2. The method of ventilating and refrigerating which comprises maintaining in a room an upper zone of relatively warm air and a lower zone of cool air, thereby displacing by gravity any heat developed in said lower cool zone, removing heated air from said upper zone, circulating air to and from said lower zone to renew and replenish the air supply of said lower zone, and cooling the air of said lower zone below the temperature of the external atmosphere.

3. The method of ventilating and refrigerating which comprises maintaining in a room an upper zone of relatively warm air and a lower zone of cool air, removing warm air from said upper zone, circulating air to and from said lower zone to renew and replenish the air supply of said lower zone, refrigerating the air of said lower zone below the temperature of the external atmosphere, and exchanging the refrigerating value of the air extracted from said lower zone into a fresh volume of air to be subsequently introduced into said lower zone.

4. The method of ventilating and refrigerating which comprises maintaining in a room an upper zone of relatively warm air and a lower zone of cool air, removing warm air from said upper zone, circulating air to and from said lower zone, exchanging the refrigerating value of the air extracted from said lower zone into the fresh air current flowing to said lower zone, and applying a refrigerant to said fresh air current after such exchange.

5. The method of ventilating and refriger-

erating which comprises, in a room the lower portion of which forms a substantially tight container therefor, establishing a stratum of air of lower temperature than 5 that of the external atmosphere and above said cool stratum of air a stratum of relatively warmer air, maintaining said lower cool stratum of air at substantially uniform volume, and removing warm air from the 10 upper stratum in said room.

6. A ventilating and cooling apparatus comprising in combination with a room, an air exit near the top thereof to permit the escape of warm air, air inlet and exit ports 15 through the walls of the lower portion of the room, means to circulate a fresh supply of air through the lower portion of the room from said inlet ports to said exit ports, means to initially cool the air before it enters 20 said inlet ports by exchanging the refrigerating value of the air leaving the cool air exit ports thereto, and means to subsequently further cool the air supplied to said cool air inlet ports.

25 7. A ventilating and refrigerating apparatus comprising in combination with a room, an air exit near the top thereof to permit the escape of warm air, means to control the flow of warm air through 30 said warm air exit, air inlet and exit ports through the walls of the lower portion of the room, means to circulate a fresh supply of air through the lower portion of the room from said inlet ports to said lower exit 35 ports, and means to purify and refrigerate the air supplied through said inlet ports.

8. A ventilating and cooling apparatus

comprising in combination with a room, an air exit near the top thereof to permit the escape of warm air, air inlet and exit ports 40 through the walls of the lower portion of the room, means to circulate fresh air through the lower portion of the room from said inlet ports to said exit ports, and means to cool the air supplied through said inlet 45 ports to a temperature lower than that of the external atmosphere.

9. In a ventilating and refrigerating apparatus, in combination with a room the lower portion of which forms a substantially 50 tight container for cool air, means to maintain a stratum of substantially uniform volume and of a temperature lower than that of the external atmosphere in the lower portion of said room, and an exit port to conduct 55 warm air from the upper portion of said room.

10. In a ventilating and refrigerating apparatus, in combination with a room the lower portion of which forms a substantially tight container for cool air, an inlet port to supply air to the lower portion of said room, means to refrigerate the air supplied through said inlet port to a temperature lower than that of the external atmosphere, and an exit port to conduct warm air from the upper portion of said room.

In testimony whereof I have affixed my signature in the presence of two witnesses.
